UNITED STATES PATENT OFFICE.

THOMAS E. IBBERSON, OF MINNEAPOLIS, MINNESOTA.

DISTRIBUTING-SPOUTS.

1,187,324.

Specification of Letters Patent. Patented June 13, 1916.

Application filed December 21, 1915. Serial No. 67,993.

To all whom it may concern:

Be it known that I, THOMAS E. IBBERSON, citizen of the United States, resident of Minneapolis, county of Hennepin, State of Minnesota, have invented certain new and useful Improvements in Distributing-Spouts, of which the following is a specification.

The object of this invention is to provide an apparatus by means of which grain from a plurality of elevator legs can be spouted to groups of bin openings arranged on the arcs of concentric circles.

A further object is to provide a spouting apparatus of compact form, which will require comparatively little space for mounting and operation.

The invention consists generally in various constructions and combinations, all as hereinafter described and particularly pointed out in the claims.

In the accompanying drawings forming part of this specification, Figure 1 is a perspective view of a pair of elevator legs and a bin distributing floor, showing my improved distributing spouts applied thereto, Fig. 2 is a side elevation, partially in section, illustrating the preferred manner of supporting and operating the distributing spouts.

In the drawing, 2 and 3 represent a pair of elevator legs and 4 is a distributing floor having groups of bin openings 5 and 6 therein. These openings are arranged on the arcs of concentric circles and the corresponding openings of the two groups communicate beneath the distributing floor with the same spout 7 for delivering the grain from these two openings to the same bin. The elevator legs have trunks 8 and 9 to which the grain is delivered by elevating buckets, not shown.

The trunk 8 has a spout section 10 telescoping therewith and at the lower end of the section 10 is an elbow 11 mounted to rotate freely on the section 10 and supported by the upright standard 12. A spout 13 is pivoted at 14 on the elbow 11 and has a lower end adapted to enter any one of the bin openings 6 as the spout is rotated on its bearings over said openings. A yoke 15 is mounted on the standard 12 and supports the spout 13 and is provided with a lever 16 having an anti-friction roller 17 bearing on the underside of the spout and an operating

cord 18 is attached to said lever for tilting it and raising the spout 13 out of the bin opening. A wheel 19 is mounted on the lower portion of the standard 12 for rotating it and the spout 13 over the bin openings. This is all well known construction in distributing spouts and I make no claim to the same herein. A hopper 20 has a sleeve 21 loosely mounted on the spout section 10 and free to revolve thereon and antifriction wheels 22 mounted on said hopper have bearings on a track ring 23 that is secured to the lower portion of the spout section 10, whereby the hopper is supported in a horizontal position with freedom of rotary movement. The trunk 9 communicates with this hopper and rotation of the hopper is effected by means of a cable seated in a circular track or way 24. The hopper 20 has a spout extension 25 to which a spout section 26 is pivoted, the lower end of said spout section being mounted to enter the openings 5 of the outer group in the distributing floor for delivery of the grain from the trunk 9 to the bin openings. Vertical movement of the spout section 26 is effected by means of a cable 27 attached to the spout section and extending upwardly to a horizontal arm 28 carried by a lever 29 and having a depending part 30 that is vertically movable in a guide 31. This arm is free to oscillate in its supports with a horizontal movement of the hopper 20 and the spout section 26 and also has a vertical movement to provide for the tilting of the spout section 26 when it is lowered to enter the bin opening or raised to be separated therefrom.

With this apparatus the grain from a pair of elevator legs can be delivered to the groups of bin openings and either distributing spout may be connected to any bin opening of the group for which the spout is designated, both spouts swinging on the same center.

I claim as my invention:

1. A plurality of grain elevator legs and a corresponding number of distributing spouts communicating with said legs and mounted to swing on the arcs of concentric circles of different radii.

2. A plurality of elevator legs and a distributing floor having groups of bin openings arranged on arcs of concentric circles of different radii, in combination with dis-

tributing spouts for said legs having a common axis and mounted to swing respectively over said groups of bin openings.

3. A pair of grain elevator legs, a distributing spout for one of said legs, a hopper concentrically mounted with respect to said distributing spout and communicating with the other elevator leg and having freedom of rotation and a second distributing spout 10 mounted on said hopper.

4. A plurality of elevator legs and a distributing floor having groups of bin openings arranged on arcs of concentric circles, in combination with concentrically mounted 15 distributing spouts for the respective legs and groups of bin openings.

5. A plurality of elevator legs and a distributing floor having groups of bin openings arranged on arcs of concentric circles, 20 and spouts below said floor communicating with the corresponding openings of said

groups, in combination with concentrically mounted distributing spouts for the respective legs and groups of bin openings.

6. A pair of elevator legs and a distributing floor having groups of bin openings arranged on arcs of concentric circles, in combination with a distributing spout for one of said legs mounted to communicate with the bin openings of one group and a 25 second distributing spout concentrically mounted with respect to said first named spout to communicate with the bin openings of the other group.

7. A plurality of grain elevator legs and 30 a corresponding number of oscillating, concentrically mounted distributing spouts therefor.

In witness whereof, I have hereunto set my hand this 30 day of November 1915.

THOMAS E. IBBERSON.
